UNITED STATES PATENT OFFICE.

ALBEN E. LUNDELL, OF NEW YORK, N. Y., AND HERBERT G. EDDY, OF BAYONNE, NEW JERSEY, ASSIGNEES, BY MESNE ASSIGNMENTS, TO WESTERN ELECTRIC COMPANY, INCORPORATED, A CORPORATION OF NEW YORK.

TELEPHONE-CALL-REGISTERING SYSTEM.

1,226,981.

Specification of Letters Patent.

Patented May 22, 1917.

Application filed January 4, 1915. Serial No. 357.

To all whom it may concern:

Be it known that we, ALBEN E. LUNDELL and HERBERT G. EDDY, citizens of the United States, residing at New York, in the county 5 of Bronx and State of New York, and at Bayonne, in the county of Hudson and State of New Jersey, respectively, have invented certain new and useful Improvements in Telephone - Call - Registering Systems, of 10 which the following is a full, clear, concise, and exact description.

This invention relates to call registering in a telephone exchange system.

Its objects are to render ineffective at- 15 tempts to make more than one registration of a single call, to prevent registering more than one call at a time, and to avoid registering an unsuccessful call. It is especially applicable to a system in which each op- 20 erator's position is equipped with a sequence switch for each cord or other connecting circuit, controlling in a plurality of resting positions the connection of the operator's telephone with calling lines.

25 In known systems, this sequence switch is automatically advanced from a normal position to a listening-in position when connection is made with a calling line and thereafter is advanced to a listening-out position, the lat- 30 ter movement being brought about by the operation of answering a subsequent call, and by the action of other controlling apparatus in various ways, and the operator's position is provided with a call registering 35 key associated with each connecting circuit by which a message register associated with the calling line, or a coin collector at the calling station, may be actuated.

It is desirable in such systems: first, to 40 render ineffective attempts on the part of the operator, through carelessness, to operate the call registering means more than once for any call; second, to obviate the possibility of registering more than one call at 45 a time, and third, to prevent the registration of calls to which the wanted party has not responded.

In accordance with this invention, the 50 first of these objects may be attained in a simple and effective manner under the control of the operator's sequence switch by

providing this switch with a second listening-out position beyond the one which the switch ordinarily takes, and in which it may rest pending the final disconnection of the 55 lines. Thus, the act of registering a call, which may take place either when the sequence switch is in the listening-in or the first listening-out position, causes the sequence switch to advance to the second 60 listening-out position wherein the call registering means is rendered ineffective.

The second object may be attained by a preferred organization which provides a special call registering position, into which 65 when the call registering key is depressed the sequence switch advances from its listening-in or its first listening-out position, and wherein it prevents any of the operator's other sequence switches from advancing to 70 a like position. Then, when the call registering key is released, the sequence switch advances from its call registering position to its second listening-out position, wherein further depressions of the call registering 75 key are ineffective.

The third object may be attained by pro- 80 viding means associated with the call regis- 85 tering key and actuated upon the wanted subscriber's response to a call which renders the call registering key then and only in that event effective.

Preferably the call registering means com- 90 prises, in addition to a key individual to each connecting circuit, a relay common to 95 the operator's position controllable by any key of that position and adapted to per- form two functions: first, to close the call registering circuit by way of any connecting circuit associated at the moment with it and with the depressed key; and second, to open a common sequence switch control circuit by which all the listening-in sequence switches are ordinarily enabled to pass into the reg- 100 istering position on to the second listening-out position. When, therefore, this common relay is appropriated by any individual call registering key, it becomes operative for the moment with respect to one connecting circuit only and one calling line message regis- 105 ter only, all other sequence switches which may at the time be moving forward out of

their first listening-in positions being arrested before reaching the call registering position and caused to wait in an intermediate position until the completion of the registration that is taking place.

The invention will be more fully understood by reference to the accompanying drawing wherein—

Figures 1 and 2 are circuit diagrams together illustrating a call registering system as applied to a semi-automatic telephone exchange, Fig. 1 including that portion of a connecting circuit under the control of one sequence switch, and Fig. 2 another part of the same connecting circuit apparatus controlled by another sequence switch, and certain apparatus common to a number of connecting circuits; and Fig. 3 is a circuit diagram of a calling subscriber's line equipped with a message register. Fig. 1 also indicates in skeleton outline the contacts of a series of automatic switches, a sender therefor and a line to be called. As the invention does not relate to or depend upon any particular form of switch, or upon the sender therefor if automatic switches are used, or upon the controlling circuits therefor, these details are not shown or described.

It is the function of certain switching apparatus shown in the drawings, including a plug 1 and spring-jack 2 and sets of contacts of automatic or other types of switches 3, 4 and 5, to provide a telephonic circuit between a calling station 6 and a called station 7. The calling line has associated with it the usual line relay 8, line signal 9, cutoff relay 10 and a message register 11, the latter having two windings 12 and 13 normally in series and in shunt of the cutoff relay and having a contact 14 adapted to shunt out the winding 13 when the magnet is energized. The connecting circuit shown in Fig. 1 is divided into inductive sections by windings 15, 16 and 17, 18 of a repeating coil, current being fed to the calling and called lines through these windings by a suitable battery. Associated with the switch 3 which may be called for convenience the district switch and with the other apparatus in Fig. 1 is a sequence switch 21, and associated with the apparatus of Fig. 2 is a sequence switch 22. Sequence switch 21 has a number of resting positions as follows: 1—normal, 2—awaiting sender, 3—brush selection, 4—awaiting sender, 5—group selection, 6—awaiting sender, 7—trunk hunting, 11—selection beyond the district switch, 14—ringing, 16—talking, 18—switch return. Sequence switch 22 also has a number of resting positions as follows: 1—normal, 7—listening-in, 11—first listening-out, 12—awaiting release of meter key of another cord, 14—call registering, 17—second listening-out. Each of these sequence switches may have a cyclic travel over eighteen full

positions. Master contacts, 42 for sequence switch 21, and 43 for the sequence switch 22, are provided for the purpose of advancing the switches from one to another of the resting positions. With the exception of the 70 normal, listening-in and the operating (12, 14) positions of sequence switch 22 all resting positions (11 and 17) are termed as sub-normal or listening-out positions. In these 75 positions of rest of sequence switch 22 the connection is maintained established, and therefore no circuit changes occur.

There are provided for registering calls, a call registering key 23 which is individual to each connecting cord circuit, and a call 80 registering relay 24 which is individual to the operator's position and therefore common to all of the connecting circuits thereof. Associated with this relay 24 may be provided a position meter 25 controlling in a 85 local circuit a lamp signal 26, which indicates the successful registration of the calls. In circuit with position meter 25 is a special source of current 27 which is brought into circuit upon the operation of the relay 90 24 for the purpose of supplying sufficient current to energize the line message register, such as the register 11 of a calling line.

Associated with each operator's position is an operator's telephone set 28 by means 95 of which the wants of calling subscribers may be ascertained. There is also provided for the connecting circuit a cord relay 29 which responds when connection is established with the calling line, a supervisory 100 lamp signal 31 for the calling line, a ringing lamp signal 32 which remains lighted when a connection is established to the called line and before the called subscriber responds, and a supervisory lamp signal 33 controlled by the called subscriber after his 105 response. These signal devices are under the control of supervisory relays 34 and 35.

The sender indicated within a dotted rectangle in the lower part of Fig. 1, is of substantially the same type as the one disclosed in a Patent No. 1,168,319 to A. E. Lundell. The details of the sender and the cord finder switch, by means of which the sender may be associated with a trunk line, are not disclosed in the present application. The circuits for controlling the operation of sequence switch 21 have been simplified for the sake of clearness. The conductors leading from the sender to sequence switch contacts 110 108 and 109, are included in a fundamental circuit that may be traced in part in the mentioned patent to Lundell from the lower contacts of sequence switch spring 243 (Fig. 1), conductor 244, the third wiper of the 115 cord finder switch X (Fig. 2), conductor 324, sequence switch contact 325, the winding of a stepping relay 402 (Fig. 3), the right-hand armature and back contact of a 120 counting relay 403, the upper contact of a 125 130

sequence switch spring 404, conductor 328, the fourth wiper of the cord finder switch X (Fig. 2), conductor 235, and the lower contacts of sequence switch spring 234 (Fig. 1).
 5 Upon the closure of a contact 38 at the sender, the listening key sequence switch 22 may be driven out of its listening-in position 7, as will be hereinafter set forth. A corresponding circuit, by means of which
 10 the listening key sequence switch 100 of the mentioned patent to Lundell may be driven out of its listening-in position 5, may be traced in the following manner: from grounded battery, through the power mag-
 15 net of sequence switch 100, the upper contact of sequence switch spring 111 (Fig. 1), conductor 112, the left-hand back contact and armature of relay 348 (Fig. 2), the upper contact of a sequence switch spring 435 (Fig. 3), and the upper contact of a se-
 20 quence switch spring 335 (Fig. 2), to ground. Thus it will be seen that the contact 38 corresponds to the upper contact of sequence switch spring 335 of the mentioned
 25 patent. Under the control of a contact 37 at the sender, a relay 36 may be operated to advance the sequence switch 21 from position to position. The relay 36 corresponds to relay 212 (Fig. 1) of the Lundell patent,
 30 and the contact 37 to the lower contact of se-
 35 quence switch spring 404 (Fig. 3). Upon the setting of selector 3, the sequence switch 21 is moved out of position 11 into position 14 by a circuit closed in a contact 39 at the
 40 sender. This contact 39 corresponds to the upper contact of sequence switch spring 429 (Fig. 3) of the Lundell patent. When the district switch 3 finds an idle trunk, a contact 41 is closed for causing the sequence
 45 switch 21 to move out of its trunk-hunting position 7. A similar circuit may be traced in the mentioned patent in the following manner: from ground, through the right-
 50 hand armature and back contact of relay 210 (Fig. 1), the left-hand armature and back contact of relay 212, the lower contact of sequence switch spring 226, and the power magnet of sequence switch 200 to grounded battery 202, the contact 41 corre-
 55 sponding to the right-hand back contact of relay 210.

The operation of the system more in detail is as follows: Assuming that the subscriber at station 6 desires a connection with the line of station 7. The line signal 9 responds upon the energization of the line relay 8 in the usual way and the operator answers the call by inserting the plug 1 of a connecting cord circuit in the spring-jack 2.
 60 This brings the cord relay 29 into a circuit with the cutoff relay 10 and message register 11 as follows: ground, 29, 44, 45, 46, thence in parallel branches 10 and 12, 13 to battery. The cord relay 29 and the cutoff relay 10 are
 65 actuated, but the message register 11 is not

because of the high resistance of its winding 13 and the insufficiency for message regis-
 70 tration of the source of current in the circuit. The cord relay closes at its contact 47 a circuit—ground, 47, 48, 22, battery which sends the sequence switch 22 out of normal position 1 into its listening-in position 7. In its advance to the latter position, there is closed a contact 49 connecting ground to a common wire 51 leading to all contacts, such as the
 75 contact 52, of the various sequence switches, such as 22, of the other connecting circuit of the same operator's position. Thus any other listening sequence switch happening at the moment to be resting in position 7 will be caused to move out of that position. As the sequence switch 22 moves into position 2, there is also closed at contact 53 a circuit—
 80 ground, 54, 53, 21, battery, which sends the district sequence switch 21 out of its normal position 1 into position 2 where it awaits control by the sender. When the listening sequence switch 22 reaches position 7, the operator's telephone set 28 is connected at contacts 55 and 56 in a bridge of the circuit to the calling line. The operator now ascer-
 85 tains the wants of the calling subscriber and proceeds to adjust the sender or in any other manner controls or directs the switching operations required to set up the connection to the wanted line. During the progress of the sender operation, contact 37 is closed and opened several times, causing repeated ac-
 90 tions and reactions of relay 36. This effects the progressive movement of the district se-
 95 quence switch 21 from position 2 to 3, 3 to 4, 4 to 5, 5 to 6, and 6 to 7. Thus, when the front contact 57 of relay 36 is closed, there is provided a circuit—ground, 57, 58, 21, bat-
 100 tery which is closed when the sequence switch is in position 2, 4 or 6, and likewise when the back contact 59 of that relay is closed there is provided a circuit—ground, 59, 61, 21, battery for the sequence switch in positions 3 and 5. In position 7, which may be assumed to be a trunk hunting position of the district switch 3, there is closed a circuit—ground, 41, 62, 21, battery which sends the sequence switch into position 11 wherein it may control the operation of the other au-
 105 tomatic switches 4 and 5, contacts 108 and 109 being provided to connect the sender in circuit with these switches. At the end of the sender operation, contact 39 closes a circuit—ground, 39, 63, 21, battery which sends the district sequence switch out of position 11 into the ringing position 14, and contact 38 closes a circuit—ground, 38, 51, 52, 22, bat-
 110 tery which sends the listening sequence switch out of its listening-in position 7 to its first listening-out position 11.

When the called party at station 7 re-
 115 sponds to the call, given in the usual way by ringing current applied to his line, there is closed a battery circuit to the called line 130

which includes the supervisory relay 35, as follows: battery, 18, 35, 104, 3, 4, 5, 7, 5, 4, 3, 105, 17, ground. This relay thereupon closes a circuit—ground, 64, 65, 66, 21, battery which sends the district sequence switch out of ringing position 14 into talking position 16. It is noted that in the ringing position 14, there had been closed a circuit—ground, 67, 68, 32, 69, battery which had lighted the ringing lamp 32. Then, as the district sequence switch moved into position 16, this circuit was opened at contact 68 and a circuit—ground, 67, 71, 33, 69 battery was closed. The latter circuit includes the supervisory lamp 33, but the lamp is for a moment shunted by a resistance 72 in series with sequence switch contact 106 and contact 64 of the supervisory relay 35. While the calling subscriber's line is closed and the district sequence switch is in positions 14 to 16, there is closed a circuit—battery, 73, 31, 74, ground which includes the calling supervisory lamp 31. At this time, however, the lamp 31 is shunted by a resistance 75 in series with sequence switch contact 107 and contact 76 of the calling supervisory relay 34.

As the district sequence switch moves into talking position 16, there is closed at contact 77 a path for a control circuit which, as will now be explained, enables the operator to register the call on the calling subscriber's register 11. The registration is effected by the depression of the call registering key 23. This act closes a circuit at contact 78 which sends the listening sequence switch out of position 7, and through 11 if it had been resting in position 7, or out of position 11 if it had been in that position, as follows: ground, 47, 78, 79, 22, battery. If the sequence switch has been resting in position 7, this circuit causes it to advance first to position 11 in which the circuit is again closed, and then from 11 to 12 where it continues to be closed. Thus, the sequence switch is caused without stopping to advance to the call registering position 14. In the latter position, there is closed a circuit for energizing the message register relay 24, as follows: ground, 47, 78, 81, 77, 24, battery. It should be noted that when the listening sequence switch had moved into position 14, it had switched the circuit of the cord relay 29 to the cutoff relay 10 from the single sequence switch contact 44, 55 to a pair of such contacts 82 and 83 so as to include a back contact 84 of the message register relay 24. Therefore, when this relay is energized, it opens the cord relay circuit and closes another for the cutoff relay 60 and message register portion thereof by way of the position meter 25, as follows: 27, 25, 85, 82, 45, 46, thence in parallel branches through the cutoff relay 10, and message register 11, to battery. The resistance of 65 the winding of the position meter 25 may

be less than that of the cord relay 29, so that the current in the new circuit is stronger than that in the original circuit through the cord relay 29; also the battery 27 assists the battery at the other end of the circuit and the current now existing in the windings 12 and 13 of the message register 11 is thus sufficient for its operation. In position 14, the message register relay remains energized in a circuit—battery, 24, 75 77, 81, 78, 80, ground. The register magnet closes at contact 14 a shunt about the winding 13, causing the position meter 25 which is marginal to receive sufficient current to operate and to close the local circuit for the signal lamp 26.

Upon the release of the key 23, the listening sequence switch 22 advances to its second listening-out position, by reason of the reaction of relay 24 and the closing at contact 86 of a circuit—ground 87, 86, 92, 22, battery. Subsequent depressions of the key 23 can have no effect while the sequence switch is in that position because the circuit of relay 24 is open at contact 81. Therefore the line message register 11, if perchance it does not remain energized in its circuit now restored, through the cord relay 29, cannot be again caused to register and also the position meter cannot again be caused to count that call.

Furthermore, when the call registering key 23 had been depressed, it had opened the contact 86. The purpose of this is to prevent the listening sequence switch 22 from advancing at the moment beyond position 14, provided contact 77 of the district sequence switch 21 had not closed. Thus, in case the called subscriber had not answered the call at the time the operator depressed the call registering key 23, the listening sequence switch 22 would have advanced in the manner already stated to position 14 and would have remained there as long as the key is held down, notwithstanding the failure of the message register relay 24 in this event to open its contact 87. And if, in the meantime, that is to say while the key 23 is held depressed, the called subscriber should respond so that the district sequence switch 21 moves into its talking position 16, causing contact 77 to close, the registration of the call would still take place, for the message register relay 24 would still be energized.

It is to be noted also that the message register relay 24 controls at its back contact 87 a path which, in a manner now to be stated, prevents more than one listening sequence switch from entering at the same time the call registering position 14. In order to explain this, let it be assumed that the message register relay 24 is at the moment energized by reason of the depression of a call registering key, such as the key 23, of 130

some other connecting circuit than the one shown in the diagram. In such event contact 87 is held open. And let it be assumed that the listening sequence switch 22 of the connecting circuit shown in the diagram is moving out of position 11 by reason, we will say, of a switch restoring operation.

Switch restoration may have occurred by reason of the operator having withdrawn the plug 1 from the spring-jack 2, in which event the circuit for the cord relay 29 would have been broken and its back contact 88 closed, completing a circuit for the listening sequence switch 22 as follows: ground, 88, 89, 91, 22, battery. This would have sent the listening sequence switch out of position 11, causing it to move into position 12 wherein it would have remained temporarily under the assumed condition, because no circuit is closed for moving it out of that position, there being an open connection at contact 87 of the message register relay 24. By reason of these conditions of the circuits, therefore, only one listening sequence switch of an operator's position can enter the call registering position at a time, and only one call can be registered upon each depression of the key 23.

Assume a case now in which the message register relay 24 is not energized during a switch restoring operation. There is then completed a circuit by way of contact 87 for sending the listening sequence switch 22 out of position 12 and also out of position 14, as follows: ground, 87, 86, 92, 22, battery. The sequence switch 22 in such event moves on to position 17 wherein the circuit previously traced, by way of back contact 88 of cord relay 29 and listening sequence switch contacts 89 and 91, is again closed, so that this sequence switch moves on from position 17 to its normal position 1. In the latter position, the listening sequence switch closes at contact 93 a circuit for causing the restoration to normal of the district switch 3, and its sequence switch 21, this circuit being as follows: ground, 88, 89, 93, 94, 95 battery. This circuit includes a knock-down relay 95 which closes a circuit—ground, 96, 97, 98, 21 battery, which sends the district sequence switch 21 out of talking position 16 into the switch restoring position 18, wherein is closed a circuit—ground, 96, 97, 99, 101, battery, including a switch restoring magnet 101. The district switch closes, at a normal contact 102, a circuit—ground, 102, 103, 21, battery, which sends the district sequence switch 21 out of position 18 to normal. The restoration of the district switch may in any desired manner bring about likewise the restoration of the other switches 4 and 5, used in completing the connection to the wanted line.

The invention herein described is applicable not only to message or call registering in the sense that the calls are indicated on a

message counter, but also to the operation of devices for collecting toll for telephone service by coin collectors, etc. Therefore, the term call register or call registering mechanism is used herein broadly in the sense of message counting or toll collecting.

What is claimed is:

1. In a telephone exchange system, the combination with a calling line, adjustable means for listening-in and listening-out, a call register, controlling apparatus for said register operable when said means is adjusted to listen in, and mechanism responding to the act of registering a call for adjusting said means to listen out.

2. In a telephone exchange system, the combination with a calling line, adjustable means for listening-in and listening-out, a call register, controlling apparatus for said register operable when said means is adjusted to listen in, and apparatus responding to the act of registering a call for adjusting said means to listen out for rendering said controlling apparatus ineffective a second time for that call.

3. In a telephone exchange system, the combination with a calling line, an operator's listening-in and listening-out switch, call register controlling mechanism operable when the operator has listened in and thereafter until the call is registered, and means responding to the act of registering a call for adjusting said switch to listen out if the operator is at the moment listening in and for rendering said register controlling mechanism ineffective a second time for that call.

4. In a telephone exchange system, calling line answering means, an operator's sequence switch having a plurality of resting positions, means for advancing said switch to a listening-in position when the operator answers a call, call registering mechanism operable when said switch is in said listening-in position, and means responding to the act of registering a call for advancing said switch to a position wherein the said registering mechanism is ineffective.

5. In a telephone exchange system, the combination with calling lines, an operator's telephone and call registering mechanism, of a sequence switch adapted to control the connection and disconnection of said telephone with said lines, said sequence switch having a listening-in, a first listening-out, call registering, and a second listening-out position, means for advancing said sequence switch out of said listening-in position and said listening-out position and for operating said call registering mechanism when it reaches said call registering position, and means for advancing said sequence switch to said second listening-out position and for rendering said call registering mechanism ineffective therein.

6. In a telephone exchange system, an

- operator's sequence switch having a listening-in and two listening-out positions, a call registering mechanism, an operator's key for controlling the actuation of said mechanism, means for rendering said key effective when the sequence switch is in its listening-in position or its first listening-out position and ineffective when it is in its second listening-out position.
7. In a telephone exchange system, the combination with calling lines, a plurality of connecting means therefor, operator's listening sequence switches one for each connecting means, means for advancing any one of said sequence switches to a listening-in position when the operator answers a call with the associated connecting means, means for advancing the said sequence switch thereafter to a listening-out position, a call register controlling mechanism, means for rendering said call register controlling mechanism effective as to the line connected to any one of said connecting means when the associated sequence switch has advanced to its listening-in position, and means common to a plurality of the connecting means for preventing the registration of more than one call at a time.
8. In a telephone exchange system, the combination with calling lines, called lines and connecting means therefor, of operator's listening-in means, call registering mechanism, means operated upon the response of a called line for rendering said call registering mechanism effective, and means responding to the act of registering a call for listening out if the operator is at the moment listening in and for rendering said register-

ing means in-effective for another registration of that call.

9. In a telephone exchange system, the combination with calling lines and a plurality of connecting means therefor, of apparatus for registering calls including a plurality of keys one for each connecting means and a switching relay common to a plurality of said connecting means, and means controlled by said relay for preventing the registration of more than one call at a time. 40

10. In a telephone exchange system, the combination with lines and an operator's connecting means therefor, of a controlling sequence switch and a call registering key associated with said connecting means, a registering circuit jointly controlled by said sequence switch and said key, and means operative upon the response of a subscriber of a called line for adjusting said sequence switch to a position in which a call may be registered by said key. 45

11. In a telephone exchange system, the combination with a calling line, adjustable means for listening in and listening out, a call register, controlling apparatus for said register, and mechanism responding to the act of registering a call for adjusting said apparatus to listen out. 50

In witness whereof, we hereunto subscribe our names this 2nd day of January A. D., 1915.
